ELECTRIC INCANDESCENT LAMP

Charles L. Fantur, Hanover, N. H., and Erwin E. Lehmann, East Cleveland, Ohio, assignors to General Electric Company, a corporation of New York

Application November 5, 1942, Serial No. 464,566

4 Claims. (Cl. 176—26)

This invention relates to vitreous electrical devices, and is especially adaptable for relatively small devices such as electric lamps, including incandescent lamps of candelabra and miniature types, and lamps for low voltages. An important aim of the invention is to provide a very rugged lamp capable of standing extreme vibration and shock, as on vehicles which travel over rough terrain and may have little or no protection against shock in the way of springs or the like. It affords the advantage that the lamps can be made with the same machinery and according to substantially the same methods as other lamps of similar types. Various other features and advantages of the invention will appear from the description of species and forms of embodiment, and from the drawing.

In the drawing, Fig. 1 is a tilted or perspective view of an incandescent lamp embodying the invention, the lamp being shown without the usual base for the sake of clearness of illustration; Fig. 2 is a tilted view of a lamp of somewhat different construction, equipped with a base; and Fig. 3 is a view similar to Fig. 1 illustrating another modification.

The incandescent lamp shown in Fig. 1 comprises a spherical bulb 10 with a neck 11 having a butt seal 12 which may be formed in any usual or preferred way—for example, as disclosed in U. S. Patent 1,742,153 to Stiles et al. The lamp has a plurality of associated filament mounts 15, two being here shown. Each mount 15 may be of the usual simple construction used in small lamps of the type illustrated, consisting of a pair of wire leads 16, 17 fused through an insulative or vitreous bead 18, and a bowed coiled filament 20 connected between the inner ends of the leads. From each mount 15, the current leads 16, 17 extend out through the viterous wall at the junction of the bulb neck 11 and its closure or seal 12, being sufficiently spaced from those of the other mount to insure against their coming in contact near the seal. Short circuit between the two mounts 15, 15 further inward from the seal 12 is effectively prevented by their beads 18, 18 which are each of a size to engage the other mount, so that they serve as buffers or spacers to keep a lead of either mount from touching a lead of the other. As here shown, the beads 18, 18 of the two mounts lie in substantially the same plane perpendicular to the leads 16, 17 and to the axis of the bulb 10 and its neck 11, and may normally engage or lie against one another with an elastic pressure due to resilience of the lead wires 16, 17, 16, 17. Thus there is no tendency for the mounts 15, 15 to strike one another with an impact or shock that might shatter the beads, or break the filaments 20, 20. Behind the mount beads 18, 18, and preferably outside the seal 12, the leads 17, 17 of the two mounts 15, 15 are connected together at 21, as by welding, so that the two filaments 20, 20 are connected in series between the other leads 16, 16. This may be done after the lamp has been exhausted and sealed off at 12.

15, 15 (or their beads 18, 18) to strike one another with an impact or shock that might shatter the beads, or break the filaments 20, 20. Behind the mount beads 18, 18, and preferably outside the seal 12, the leads 17, 17 of the two mounts 15, 15 are connected together at 21, as by welding, so that the two filaments 20, 20 are connected in series between the other leads 16, 16. This may be done after the lamp has been exhausted and sealed off at 12.

Fig. 2 illustrates a variant construction in which the bent or bowed filaments 20a, 20a are longer than those shown in Fig. 1, as for lamps of higher voltage, and have their bights or bends supported, substantially at mid-length of each filament, by elastic, resilient support wire 22, 22 each having one end anchored and fixed by being fused into the corresponding bead 18, and having its other end bent into a pigtail loop 23 loosely embracing the filament. In Fig. 2, the lamp is shown equipped with a candelabra base of ordinary bayonet shell and center contact type. One of the leads 16 is connected to the center contact at 24, while the other is connected to the shell contact part at 25.

25 The construction shown in Fig. 3 is distinguished by the fact that the resilient support wires 22b, 22b are bent into a gallows-like form resembling an ordinary conventional interrogation point, with looped eyes 23b, 23b at their free ends surrounding and engaging the bends of the filaments 20, 20. In other respects, the construction is essentially like what is shown in Figs. 1 and 2.

30 35 To dispense with repetitive description, various parts and features in Figs. 2 and 3 are marked with the same reference numerals as their counterparts in Fig. 1, a distinctive letter being added where such distinction seems necessary.

In all the forms of construction, the filaments 20, 20 are much stronger as against breakage by shock than one filament of the same wire size and twice the length—or of the same length and half the cross-sectional area—which would take the same voltage as the two filaments in series. In a 3 volt lamp, two filaments of 1½ volts each may be used; in a 12-16 volt lamp, two 6-8 volt filaments may be employed; in a 24-28 volt lamp, two 12-16 volt filaments are suitable. The Fig. 2 construction with the intermediate supports 22, 22 is particularly suitable for 12-16 volt lamps, and that of Fig. 3 for 24-28 volt lamps, while lamps of lower voltage do not usually need intermediate supports, because their filaments are much shorter and stronger against shock, and may be made

as in Fig. 1. All tests show that the series connection of the filaments of associated mounts makes a very much stronger construction than a single filament and mount.

What we claim as new and desire to secure by Letters Patent of the United States is:

1. A device of the character described comprising a bulb with a seal, filament mounts in said bulb comprising pairs of leads sealed through said seal and an insulative bead mechanically connecting the leads of each pair while electrically insulating them from each other, each of said beads being of a size to engage another mount and prevent short circuiting contact between the mounts, and leads of said mounts being connected together behind their beads, so as to place the filaments of said mounts in series electrically between the other leads of said mounts.

2. A device of the character described comprising a bulb with a butt seal, filament mounts in said bulb comprising pairs of leads sealed through said seal and an insulative bead mechanically connecting the leads of each pair while electrically insulating them from each other, said beads lying substantially in a common plane perpendicular to the leads, so as to prevent short circuiting contact between leads, and leads of said mounts being connected together outside said bulb, so as to place the filaments of said mounts in series electrically between the other leads of said mounts.

3. A device of the character described comprising a bulb with a seal, filament mounts in said bulb comprising pairs of leads sealed through said seal and an insulative bead mechanically connecting the leads of each pair while electrically insulating them from each other, each of said beads being of a size to engage another mount and prevent short circuiting contact between the mounts, and leads of said mounts being connected together behind their beads, so as to place the filaments of said mounts in series electrically between the other leads of said mounts.

ing a bulb with a seal, a pair of filament mounts in said bulb comprising pairs of leads sealed through said seal and an insulative bead mechanically connecting the leads of each pair while electrically insulating them from each other, the leads of the two mounts lying in approximately parallel planes and the beads of said mounts abutting one another, so as to prevent short circuiting contact between leads, and leads of said mounts being connected together outside said bulb, so as to place the filaments of said mounts in series electrically between the other leads of said mounts.

4. A device of the character described comprising a bulb with a seal, filament mounts in said bulb comprising pairs of leads sealed through said seal and an insulative bead mechanically connecting the leads of each pair while electrically insulating them from each other, each of said beads being of a size to engage another mount and prevent short circuiting contact between the mounts, leads of said mounts being connected together behind their beads, so as to place the filaments of said mounts in series electrically between the other leads of said mounts, and each mount comprising a resilient gallows support engaging the bend of a filament at its own free end, and having its other end anchored in the mount bead.
